UNITED STATES PATENT OFFICE.

VINCENT HUSVAR, OF WATERBURY, CONNECTICUT, ASSIGNOR TO SCOVILL MANUFACTURING CO., OF WATERBURY, CONNECTICUT, A CORPORATION OF CONNECTICUT.

APPARATUS FOR PRODUCING CAP SCREWS AND THE LIKE.

Application filed January 5, 1922. Serial No. 527,116.

This invention relates to a method of and apparatus for producing cap-screws or the like.

The usual commercial practice, in making cap-screws, has been to head up a cold rod to form a blank having a shank and a substantially circular head. This blank is then placed in a milling machine and the facets which form the polygonal head of the finished product are milled, giving a smooth, machined surface demanded by the trade. This milling operation is expensive and increases the cost of the screws.

It is the principal object of the present invention to provide an improved method of and means for producing cap-screws without milling the facets of the head.

With this general object in view the invention consists in the methods, combinations, details of construction, and arrangements of parts which will first be described in connection with the accompanying drawings and then more particularly pointed out.

In the drawing:

Fig. 1 is a view in vertical section of apparatus embodying the invention;

Figs. 2-5 inclusive are sectional views (enlarged) through the die, showing the parts in different progressive positions;

Fig. 6 is a front face view of the planishing die removed;

Fig. 7 is a rear face view of the cutting die removed; and

Figs. 8-11 are side views of the blank, intermediate blank, cut blank and finished product respectively.

In carrying out the invention, blanks are formed in any suitable manner, as by heading up cold a rod of the desired size. This step provides a blank with a circular head (Fig. 8). To form the facets of the head, the blank is subjected to the action of a polygonal die in such manner that the excess metal is removed by a one-way cut. That is to say, starting at the top or bottom of the head, the die cuts across the side of the head in one direction until the excess metal is cut through, as distinguished, for example, from a cutting action working from both top and bottom toward the center.

As the die cuts away the excess metal, the cut or shaved off waste metal forms a sort of flange which is pushed ahead until it reaches the top or bottom of the head

(according to the direction of cut) and is eventually removed. Fig. 9 illustrates this waste flange at the top of the head just prior to being severed. In carrying out the invention according to what is considered the best method, this waste flange, at the time it is severed from the head, is positively held or pinched. With this method, tearing of the metal on the facets is avoided and a clean cut or break is obtained.

In carrying out the invention in its entirety, the facets of the head are planished, for example, by a planishing die, and preferably this planishing operation is carried on under lubrication. This planishing eliminates any roughness left at the point where the waste flange or web is eventually cut off and as a result the facets present the smooth, clean finish demanded by the trade. Fig. 10 illustrates a blank after severance of the head and planishing of the facets.

The blank may then be trimmed in any suitable manner to remove any roughness at the juncture of the facets with the face of the head, in this instance, the top of the head. Fig. 11 shows the trimmed head.

It will be understood that to form a complete cap-screw, the shank is suitably threaded. But for the purposes of the present invention the finished product is the cut, planished and trimmed head, the threading operation being assumed.

Referring to the drawings, the invention includes a cutting die, a blank holder and means for causing relative movement between the die and the blank to cut the facets of the head with a one-way cut. In the embodiment shown, a blank (Fig. 8) with a circular head 101 is forced through a stationary cutting die. To this end, as here shown, there is provided a cutting die 12, held in a die block 13 carried by a frame 14. The die 12 has a polygonal cutting bore, as appears in Fig. 7, to cut the circular head into facets, thereby producing a polygonal head, the die here illustrated being for an hexagonal head. In the present exemplification the blank is inserted through the die shank first and the head is forced through the die as hereinafter described.

The invention includes means for holding the blank and in structures embodying the invention to the best advantage, the holding

means is so arranged as to insure concentricity between head and shank in the completed product. Although capable of various constructions, in that here illustrated as an example, a tubular holder 15 is carried by a tubular member 16 reciprocably mounted in a bushing 17 mounted in the frame. The tubular member 16 slides on a rod 18 suspended by a bracket 19 from a tie rod 20. The holder 15 has an internal bore designed to make a close fit with the shank 102 of the blank, thereby firmly holding the blank and preventing any substantial play or tilting of the blank during cutting. As a result the cut heads are uniformly concentric with the shanks.

Means is provided for moving the holder 15. Although capable of various constructions, in that here illustrated, threaded onto tubular member 16 is a grooved collar 21 engaged by a yoked lever or rocker arm 22 mounted on a rock shaft 23. Shaft 23 being rocked by any suitable means, such as a cam and rocker arm, member 16 and the holder 15 reciprocate as later described. By moving the connector 21 along the threaded portion of tubular member 16, the stroke of the latter may be adjusted with respect to the die.

The blanks may be inserted in the holder in any suitable manner, it being understood that at this time the holder is advanced into the die in some such position as shown in Fig. 2. This insertion may be done by hand or it may be accomplished by feeding and positioning means in connection with the pushing means later described. Fig. 1 illustrates, as an example, a feeding and positioning means comprising a vertically reciprocating slide 25 operated by a link 26, rocker arm 27 and suitably driven rock shaft 28. The slide 25 carries a spring gripper 29 for grasping the end of the shank in the manner shown in Fig. 1. The blanks are fed down a chute 30, and are carried to a position to be taken by the gripper 29 by a slide 31 operated by a rocker arm 32. The blanks being carried down by gripper 29 to a position opposite the die, are moved into the waiting holder 15 by the advance of the pushing element about to be described.

The invention includes means for forcing the blank head through the die, and for pinching or grasping the shaved off flange of waste metal at the time the latter is severed from the head. This may be accomplished, for example, by a two part pushing element having such differential movement that one part may act as a pinching element at the end of the pushing stroke while the other part continues the pushing stroke. Although capable of various constructions, in the present exemplification, reciprocating on a bed plate 33 is a slide 34 having in its forward end a holder 35 for a hardened

block 36. The slide 34, is reciprocated, as here shown, by a double toggle 37, 38, actuated by a pitman 39 driven by a crank 40.

The differential pusher, in the present embodiment, comprises a pusher bar 41 movable through a central bore in the pusher block 36. The forward end of pusher bar carries a spring-pressed, relatively movable pusher pin 42. The function of this pin 42 has to do with the ejection of the blanks as hereinafter described. For the purposes of forcing the blank head through the die the pusher pin 42 may be considered as one with bar 41. Bar 41 is slideable in a bushing 43 in the slide 34 and is carried by a slide block 44, movable in a channel 45 formed in the main slide 34. To give the pusher bar 41 its differential movement, there is provided, in the present embodiment, a wedge or cam 46 movable between a roller 47 carried by the main slide 34 and a roller 48 carried by the supplemental slide block 44. The wedge 46 extends through a suitable opening 49 in the slide 34 and is drawn downwardly by means of a pitman 50 operated by an eccentric 51. Any suitable means, such as a spring, may be provided for giving the slide block 44 its return relative movement.

Assuming the blank to be positioned in its holder, upon advance of the pushing element, the head of the blank is forced through the cutting die 12, pusher block 36 and pusher rod 41 operating as a unit at this time and holder 15 withdrawing as the blade advances. During this movement of the blank, the die cuts the metal of the head away, starting at the bottom of the head and working toward the top, the cut away metal forming a petal-like flange around the blank head. It will be noted that the front face of the cutting die 12 falls away from the center (see Fig. 2) and the pusher block 36 has a central boss 52, dished to accord with the rounded top of the blank. Consequently there is a space 53 for the waste flange between the die and the pusher block. As the cutting continues, the cut-away flange eventually reaches the top of the head, as shown at 103, Fig. 9. At this time, the pusher block 36 firmly pinches or grasps the waste flange between itself and the front face of die 12 and the differential pusher bar 41 now makes its relative movement to continue the pushing stroke. Under this continued advance of the blank the waste flange, while firmly held, is severed from the head, thus completing the cutting of the facets (see Fig. 8).

The invention includes a planishing die 54 and means whereby the planishing operation is effectively lubricated. Although capable of various constructions, as here illustrated, back of the cutting die is a planishing die 54 also carried by the die block 13.

This planishing die 54 has an hexagonal bore (Fig. 6) designed to planish the cut facets, thereby to remove any roughness, particularly at the point where the waste flange was severed.

To provide suitable lubrication, as here illustrated as an example, at the back of the cutting die 12 is a rim 55 provided with a groove 56 extending from the circumference of the die to its bore. Opposite this groove, the front face of the planishing die has a similar groove 57. These two grooves form a channel which communicates, through a bore 58 in the die block 13, with a pipe 59 of any suitable force feed or other lubricating system.

Means is provided for ejecting the cut and planished blanks and in constructions embodying the invention to the best advantage 20 the blank is moved against a stationary ejecting abutment by the same one-way continuous movement that carries it through the cutting and planishing dies. As here illustrated as an example, the end of rod 25 18 serves as a stationary ejecting abutment. After the blank head has passed through the planishing die, the holder 15—16 continues its backward stroke, the blank being carried against the end of rod 18 which causes the 30 blank to be ejected from the holder as the latter moves back. The ejected blank drops down the slanting runway 60 to any suitable collecting element.

Meantime, the pusher bar 41 has started 35 its return stroke. As the parts operate in a heavy lubricant there is a strong suction upon the return movement of the pusher. To prevent this suction from displacing the blank from the holder, the pin 42 is provided. As the pusher bar starts to withdraw the pin 42 is forced outward by its 40 spring and thus serves as a knock-out to prevent the blank from following the pusher bar.

The operation of the apparatus will be 45 clear from the foregoing. To sum up, however, the pushing element being withdrawn and the holder advanced (Fig. 2) the gripper 29 takes a blank from slide 31 and lowers it to a position opposite the die 12. The pushing element now advances as a unit and first pushes the blank into the die and then forces the blank head through the cutting die 12, holder 15 being withdrawn as 50 the blank is advanced. The flange of waste, cut away metal, as it reaches the top of the blank head, is grasped or pinched between the pusher block 36 and the face of the die 12 and while so grasped, is severed by 55 the die as the pusher bar 41 makes its differential movement and forces the blank head onward. Continued movement of the pusher bar 41 forces the blank head through planishing die 54 which planishes the cut faces. The pushing element now starts its

return stroke but the holder 15 continues backward to carry the blank against the pin 18, thereby to eject the blank from the holder. The holder 15 is then returned to receiving position and the pushing element 70 returns to initial position, the parts being ready for another cycle. It will be understood that the above described movements are, in many respects, more or less simultaneous.

With the construction described the blank is cut, planished and ejected by a one-way, continuous movement. By die-cutting the blank so as to form a waste flange at the extremity of the cut facets, by pinching this waste flange at the time it is severed, and by planishing the cut facets, the metal of the facets is not torn and the final surfaces have the smooth, clean finish that is commercially desirable, and this is accomplished 85 without subjecting the cap-screws to the action of a milling machine.

What I claim is:

1. In a machine of the class described, and in combination a cutting die, a holder 90 for a headed blank, means for forcing the blank head through the die including a reciprocating pusher bar, and a spring-pressed pin carried by the pusher bar and serving as a knock out to prevent the blank from following the pusher bar when the latter is withdrawn.

2. In a machine of the class described, and in combination a stationary cutting die and planishing die having aligning bores, a 100 channel for supplying lubricant to the bores of said dies, a tubular blank holder to the rear of the dies, a pusher bar, means for advancing the pusher bar toward and into the dies to push the blank through the dies, and thereafter withdrawing the same, and a spring-pressed knockout pin carried by the pusher bar for preventing the blank from following the pusher bar when the latter is withdrawn.

3. In a machine of the class described, and in combination, a hexagon cutting die, a two-part non-cutting pushing device comprising a pushing block having a bore coaxial with the bore of the die and a supplemental pusher 110 movable in the bore of the pusher block and having a diameter to permit passage through the bore of the cutting die, a hexagonal boss on the front face of the pusher block surrounding the bore of the latter, and means 115 for (a) advancing the pushing device as a unit toward the die to push the head of a blank through the die a sufficient distance to cause cutting of the facets up to a point adjacent the trailing end of the head, whereby 120 a burr of waste metal is formed adjacent such end of the head, (b) holding the pusher block in its advanced position to clamp the waste burr between the boss and the face of the die, and (c) advancing the supplemental 125

pusher alone while the pusher block is so held to continue the movement of the blank head through the die and cause severing of the waste burr while it is so clamped.

- 5 4. In a machine of the class described, and in combination, a hexagon cutting die, a planishing die rearward of the cutting die, a two-part non-cutting pushing device comprising a pushing block having a bore coaxial with the bore of the die and a supplemental pusher movable in the bore of the pusher block and having a diameter to permit passage through the bore of the cutting die, a hexagonal boss on the front face of the 10 pusher block surrounding the bore of the latter, and means for (a) advancing the pushing device as a unit toward the die to push the head of a blank through the die a sufficient distance to cause cutting of the facets 15 up to a point adjacent the trailing end of the head, whereby a burr of waste metal is formed adjacent such end of the head, (b) holding the pusher block in its advanced position to clamp the waste burr between the 20 boss and the face of the die, and (c) advancing the supplemental pusher alone while the pusher block is so held to continue the movement of the blank head through the die and cause severing of the waste burr while it 25 is so clamped and thereafter through the planishing die.

- 5 5. In a machine of the class described, and in combination, a hexagon cutting die, and non-cutting means for (a) forcing the 30 head of a blank through said cutting die a sufficient distance to cause cutting of the facets up to a point adjacent the trailing end of the head, whereby a burr of waste metal is formed adjacent such end of the head, (b) 35 clamping said waste burr against the face of the die, and (c) continuing the forcing of the head of the blank through the die in the same direction to sever the waste burr while the same is so clamped.

- 6 6. In a machine of the class described, and

in combination, a hexagon cutting die, a planishing die to the rear of the cutting die, and non-cutting means for (a) forcing the head of a blank through said cutting die a sufficient distance to cause cutting of the facets up to a point adjacent the trailing end of the head, whereby a burr of waste metal is formed adjacent such end of the head, (b) clamping said waste burr against the face of the die, and (c) continuing the forcing of the head of the blank through the die in the same direction to sever the waste burr while the same is so clamped and thereafter through the planishing die.

7. In combination, two metal-working dies arranged in tandem and having coaxial bores, the opposing faces of said dies having a channel formed therebetween leading to the bores of the dies and adapted for communication with a lubricating system.

8. In combination, two metal-working dies having bores, one die having a groove in its rear face, the other die having a groove in its front face, each of said grooves communicating with the respective die bore, the grooves being so arranged that when the dies are assembled in tandem with their bores coaxially arranged said grooves provide a channel for the delivery of a lubricant to said bores.

9. In a machine of the class described, and in combination, a die block, two metal-working dies mounted in tandem in said die block with their bores coaxial, the opposing faces of said dies having a channel formed therebetween leading to said bores, the die block having a passageway communicating with said channel, whereby a lubricant may be delivered to said bores, and means for forcing a blank through the said bores.

In testimony whereof, I have hereunto set my hand.

VINCENT HUSVAR.
